UNITED STATES PATENT OFFICE.

JOHANN GLASS, OF LEIPSIC, SAXONY, ASSIGNOR TO ADOLF KESSLER, JR.,
OF MARKNEUKIRCHEN, GERMANY.

VIOLIN-BOW.

SPECIFICATION forming part of Letters Patent No. 425,503, dated April 15, 1890.

Application filed April 9, 1889. Serial No. 306,631. (No model.)

To all whom it may concern:

Be it known that I, JOHANN GLASS, of Leip-
sic, in the Kingdom of Saxony, Germany, have
invented an Improved Bow for Stringed Mu-
5 sical Instruments, of which the following is a
specification.

This invention relates to an improved bow
for stringed musical instruments, and more
particularly to the manner of attaching the
10 hair to the frog and tip.

The invention consists in the various fea-
tures of improvement more fully pointed out
in the claims.

In the accompanying drawings, Figure 1 is
15 a sectional elevation of my improved bow.
Fig. 2 is a bottom view thereof with slide *f*
partly cut away. Fig. 3 is a side view of the
tip; Fig. 4, a section on line V V, Fig. 3; Fig.
20 5, a section on line U U, Fig. 1; Fig. 6, a side
view of the frog; Fig. 7, a section on line W
W, Fig. 6; and Fig. 8, a section on line X X,
Fig. 6.

The letter *A* represents the handle or stick
of the bow, terminating at one end in the tip
25 *A'*, and provided at the other end with the
adjustable frog *A²*.

The hair *B* is provided at each end with a
knot or is enlarged or thickened in an equiva-
lent manner, as at *i* and *a*.

30 The frog *A²* is provided with a longitudinal
groove *b*, into which opens a downwardly-ex-
tending slit *d*. The knot *a* is passed into

groove *b*, while the hair passes down and out
through the slit *d*. The groove *b* is closed by
slide *e*, and the slit *d* is closed by slide *f*. 35

The tip *A'* of the bow is provided with a
transverse groove *g*, communicating with the
downwardly-extending slit *h*. The knot *i* is
passed into the groove and the hair projects
out of the slit. A slide *k* serves to close the 40
groove *g*.

The advantage of this bow is that the hairs
are all subjected to the same tension and that
they can be readily inserted.

What I claim is— 45

1. The combination of handle *A* with frog
A², having a groove and a slit communicating
with the groove, and with the hair *B*, having
a knot that is received by the groove, substan-
tially as specified. 50

2. The combination of handle *A*, having a
tip, with a frog, the tip and frog being pro-
vided with grooves and communicating slits,
and with hair *B*, being knotted at the ends to
be received by the grooves, and with the slides 55
e f k, substantially as specified.

In testimony whereof I have signed my
name to this specification in the presence of
two subscribing witnesses.

JOHANN GLASS.
